DRAIN CONNECTOR FOR SHOWER BATH
RECEPTORS

Benjamin F. Birdwell, Louisville, Ky., assignor to
Porcelain Metals Corporation, Louisville, Ky.,
a corporation of Kentucky

Application October 5, 1944, Serial No. 557,342

7 Claims. (Cl. 4—146)

1

In manufacturing shower bath receptors of the type having an upper pan and a lower base rim, it has been proposed to make the pan and rim of the lightest gauge sheet metal considered practical, bolt or weld the parts together with the pan resting upon the upper end of the rim, clean the assembly by a pickling operation, coat it with porcelain enamel and then fire it to fuse the enamel. The receptor is then provided with a drain connector comprising a cylindrical casting having: an outwardly turned top flange resting on the upper face of the rim of the drain opening in the pan; and a jam nut threaded to the outer surface of the casting and cooperating with the top flange to clamp the interposed rim of the drain opening and thereby rigidly secure the connector casting to the receptor. The clamp joint is sealed at the factory by a suitable compound or plastic smeared over the upper face, and a gasket placed against the lower face, of the rim of the drain opening.

In installing the receptor in the field, it is lowered into its final position wherein the base rim rests upon the foundation floor and the lower end portion of the drain connector casting extends, in outwardly spaced relationship, around the upper end portion of a drain pipe. The annular pipe joint space between the upper end portion of the drain pipe and the surrounding connector casting is then caulked to seal the pipe joint against leakage and thus complete the drainage connection. In the foregoing arrangement, the periphery of the pan is supported through the base rim upon the foundation floor. It is highly desirable to support the pan around the drain connection and it has been proposed to accomplish this by resting the lower end of the connector casting upon the foundation floor. This, however, presents a problem which is difficult to overcome.

For example, the floor of the pan is always characterized by a condition known as "loose metal" which prevents it from being rigid and causes it, when pressed, to flex. Because of this loose metal, the floor of the pan, during the firing of the enamel, tends to sag to a varying but permanent degree so that its final elevation cannot readily be predetermined; hence the final elevation of the lower end of the connector casting likewise cannot be predetermined. Accordingly it has been found necessary to use a connector casting of a shortened length such that its lower end will be spaced, above the foundation floor, a varying extent depending upon the degree of sag and to bridge such space with shims. Here again, however, the required overall thickness of the

2

shims cannot readily be determined, except through trial and error, which often involves the repeated removal and replacement of the receptor during the installation process to permit repeated changes in the overall thickness of the shims until the proper thickness is finally determined. Because this detail is bothersome, there is a tendency either to overlook it entirely or perform it improperly so that in many instances the pan is not properly supported around the drain, causing it to deflect when walked upon and, as a result, to be objectionably noisy.

Another objection to the foregoing type of drain connection is that the plumber installing the receptor may neglect to retighten the jam nut in the event it becomes loose prior to or during the installation operation or that the installation may be subject to vibration from the foundation floor or drain pipes and the like, causing the jam nut to become loose during the use of the installation. This results in leakage at the clamp joint which is highly objectionable since its correction normally requires the dismantling of the installation or the opening of the foundation floor from the under side to provide sufficient access to the jam nut for tightening purposes. The clamp joint, and its attendant objections, may be overcome by welding the drain connector to the floor of the pan, but this introduces enameling difficulties which are equally objectionable and does not overcome the difficulties incident to the provision of a central support.

The present invention relates to, and its principal object is to provide, a drain connector which overcomes all of the foregoing objections and limitations.

Another object is to provide a drain connector which is relatively inexpensive to manufacture, which eliminates "loose metal" in the floor of the pan and thus enables the final elevation of the lower end of the drain connector to be predetermined, which eliminates the clamp joint and its attendant objections without introducing other objections, which simplifies the installation operation and which results uniformly in a rigid, firmly supported and quiet pan.

A further object is to provide an improved method of producing a receptor pan and drain connector assembly.

50 A receptor embodying the invention is disclosed in the accompanying drawing wherein:

Figure 1 is a plan view;
Figure 2 is a section along line 2—2 of Figure 1, with the receptor resting upon the foundation floor; and

Figure 3 is an enlarged section along line 3—3 of Figure 1.

The receptor illustrated conventionally includes: an upper pan 1 having side walls 2, and a bottom wall or floor 3, which slopes from its periphery downwardly to a central drain opening; a strainer 4 over the drain opening; a lower base or foundation rim 5, having an upper marginal flange 6, which supports the periphery of the pan 1, and an inclined lower marginal flange 7, which rests upon the foundation floor 8; a drain opening 9 in the foundation floor; and a drain pipe 10, in the opening 8.

In accordance with my invention, the drain connector is formed integrally with the floor of the pan. The integral connector cannot be satisfactorily formed by a welding operation since, as previously pointed out, welding introduces well known enameling difficulties without overcoming the problem incident to a central support. Neither can the integral connector be formed by a drawing operation because there is insufficient metal around the opening for drawing purposes. But even if a drawn receptor were possible, it will be appreciated that the central support problem would remain untouched. I have found, however, that sufficient metal, for the formation of an integral connector by a shaping or drawing operation, can be provided around the drain opening area by an operation known as "gathering" metal and, that, when an integral connector is so formed, all of the foregoing difficulties are substantially eliminated without introducing any offsetting disadvantages.

Accordingly, I propose to employ the well known metal gathering process for gathering sufficient metal around the drain opening area for connector forming purposes and then to form the gathered metal into an integral cylindrical connector 11. Specifically the process is preferably carried out to form a connector 11 having an upper outwardly turned flange or rim 12, which is depressed from the body of the floor 3 sufficiently to place the strainer 4 at or slightly below the adjacent floor level, and a lower inwardly turned flange 13 which defines the pipe receiving opening.

An unexpected result of this application of the gathering and forming process is that it produces a substantially rigid and unyielding floor 3 which, during the enamel firing operation, either does not sag or for some other reason does not change the original elevation of the lower end of the connector 11. While the precise reason for this is not definitely known, it is believed to be due to either or both the substantial elimination of "loose" metal and the increased strength imparted to the floor metal during the gathering operation, alone or in combination with the forming operation. Whatever the cause may be, the present invention results in the formation of a drain connector whose original elevation is its final elevation. The advantage of this is that the drain connector may be originally formed so that its lower end, in this case the flange 13, lies at a predetermined level corresponding to the level of the foundation floor 8 whereby, when the receptor is installed, the floor 3 will be supported both peripherally and centrally.

Another advantage of the present invention arises from the fact that it produces a connector, the lower end of which may be used to provide a central support during the enamel firing operation. Heretofore the central portion of the receptor floor could not be supported during the

firing operation because the connector had to be permitted to drop to whatever elevation the sag permitted. In the present case, with the sag eliminated, the elevation of the connector remains substantially the same during the firing operation. However, by supporting the floor of the receptor through the connector during the firing operation, a certain degree of strain or pull on the side walls of the pan is eliminated which heretofore has had a tendency to warp the side walls somewhat.

In carrying out the invention, a flat blank of sheet metal is provided having an inner area corresponding to the floor 3 and containing a central drain area, and an outer marginal area corresponding to the walls 2, of the pan 1. The floor area is subjected to a metal gathering operation which, while well known, may be outlined as follows: the metal is flexed or pressed in one direction between the center of the drain area and the outer rectangular marginal area to form a wide shallow bulge extending outwardly in one direction from the major plane of the sheet; it is then flexed or pressed in the opposite direction to form a slightly narrower but deeper bulge extending outwardly in the opposite direction from the major plane of the original sheet; and steps of this character are continued until a sufficiently narrow and deep bulge is obtained from which the final connector may be readily formed as desired either by an operation involving shaping the connector and providing a bottom opening or by a drawing operation in which a small hole is formed at the bottom or center of the bulge and a drawing operation performed which draws the metal to the desired shape and, at the same time, enlarges the bottom hole to drain pipe receiving proportions. Where a drawing operation is performed, the side walls and sloping floor can be drawn to final shape at the same time. After the original blank has thus been processed to finished form, it is united to the base rim to form the final assembly which is then pickled, enameled and fired.

An enameled receptor constructed in accordance with the present invention can be installed simply by lowering it in alignment with the drain pipe opening until the lower marginal flange 7 of the base, and the inwardly turned flange 13 of the connector, rest on the foundation floor. The annular pipe joint space above the connector flange 13 and between the upper end portion of the drain pipe 10 and the surrounding connector 11 may then be caulked to seal the pipe joint against leakage and complete the drainage connection.

Where the caulking is performed, carelessly, or under extreme pressure, there is a possibility that the enamel on the connector, or the connector itself, may be damaged. To provide against this, I propose to place or nest within the connector a protecting sleeve 14 having an outwardly turned flange 15 at its upper end and an inwardly turned flange 16 at its lower end. The nesting sleeve 14 preferably is made of a rust proof metal, such as brass, copper or stainless steel and may be secured in place by a mastic 17. It may be additionally anchored by providing it with a number of openings 18 to receive caulking material during the caulking operation. Its upper flange 15 provides a convenient anchorage for the strainer 4 although the latter may otherwise be anchored by well known spring pressed means frictionally engaging the connector walls. If desired, its lower flange 16 may be downwardly turned as at 19 to form a flared mouth which facilitates

the alignment of the receptor with the drain pipe.

The present invention not only eliminates the difficulties incident to the clamp joint and central support without introducing offsetting disadvantages, but it also: substantially reduces the manufacturing cost since the integral connector may be quickly and inexpensively made at a cost equal approximately to 20% or less of the cost of a cast connector; substantially eliminates the breakage to which a cast connector is subject; and produces an exceptionally rigid and quiet floor.

Having described the invention, I claim:

1. An improved shower bath receptor of the type having a floor of sheet metal of relatively light gauge and containing a drain opening comprising: a metal connector integrally connected to the floor to depend from the periphery of the drain opening, said connector being composed of floor metal.

2. The receptor of claim 1 wherein: the connector has an upper outwardly turned flange, which is integrally connected to but depressed from the adjacent portion of the floor, and a lower inwardly turned flange which defines a drain pipe receiving opening.

3. An improved receptor having a sheet metal floor containing a drain opening comprising: a cylindrical drain connector depending from and integrally connected to the rim defining the drain opening; a protective sleeve nested within the connector and adapted to receive and be secured in sealing relation with a drain pipe; and means between the sleeve and connector for anchoring the sleeve to the connector and sealing any space therebetween against leakage.

4. An improved shower bath receptor pan of the type adapted for connection to a drain pipe, comprising: a single continuous body of sheet metal which extends inwardly from the periphery of the pan and slopes downwardly to a drain section, to form a downwardly sloping floor having a drain opening at the drain section, and then extends annularly downward from the drain opening, to form a depending sleeve-like connector open at its lower end and providing, in its lower-end portion, a central area for receiving said drain pipe projecting upwardly through its lower end opening and a surrounding caulking space for receiving caulking material to seal the connection between the connector and pipe, said caulking space being accessible for caulking purposes through the drain opening of said floor.

5. The pan of claim 4 wherein said single continuous body of sheet metal also extends annularly inward from the lower end of the connector to form a drain pipe receiving opening and to provide a bottom wall for the caulking space.

6. An improved pan for a shower bath receptor of the type adapted for connection to a drain pipe and having means, supported upon a suitable foundation at one level, for engaging the pan adjacent its periphery to support the pan at a predetermined higher level, comprising: a single continuous body of sheet metal which extends inwardly from the periphery of the pan and slopes downwardly to a drain section, to form a downwardly sloping floor having a drain opening, and then extends annularly downward from the drain opening substantially to the foundation level to provide a central support for the pan and to form a depending sleeve-like connector open at its lower end and providing, in its lower-end portion, a central area for receiving said drain pipe projecting upwardly through the foundation level and through the lower end of the connector and a surrounding caulking space for receiving caulking material to seal the connection between the connector and drain pipe, said caulking space being accessible for caulking purposes through the drain opening of said floor.

7. The pan of claim 6 wherein said single continuous body of sheet metal also extends annularly inward from the lower end of the connector to form an inwardly directed flange having a drain pipe receiving opening and providing a bottom wall for the caulking space and a seat for supporting the floor of the pan about the drain opening upon a foundation support at the foundation level.
